(57) **CLAIM**

The ornamental design for a control knob for a rifle telescope, as shown and described.

DESCRIPTION

FIG. 1 is a perspective of a first embodiment of the control knob of our new design shown mounted on a rifle scope; FIG. 2 is a top perspective of the control knob of FIG. 1; FIG. 3 is a bottom perspective of the control knob of FIG. 1; FIG. 4 is a top plan view of the control knob of FIG. 1; FIG. 5 is a bottom plan view of the control knob of FIG. 1; FIG. 6 is a left side elevation view of the control knob of FIG. 1; FIG. 7 is a right side elevation view of the control knob of FIG. 1; FIG. 8 is a front elevation view of the control knob of FIG. 1; FIG. 9 is a rear elevation view of the control knob of FIG. 1; FIG. 10 is a perspective of a second embodiment of the control knob of our new design shown mounted on a rifle scope; FIG. 11 is a top perspective of the control knob of FIG. 10; FIG. 12 is a bottom perspective of the control knob of FIG. 10; FIG. 13 is a top plan view of the control knob of FIG. 10; FIG. 14 is a bottom plan view of the control knob of FIG. 10; FIG. 15 is a left side elevation view of the control knob of FIG. 10; FIG. 16 is a right side elevation view of the control knob of FIG. 10; FIG. 17 is a front elevation view of the control knob of FIG. 10; and, FIG. 18 is a rear elevation view of the control knob of FIG. 10. The rifle telescope body shown by dashed lines in FIGS. 1 and 10 is for illustrative purposes only and forms no part of the claimed design.

1 Claim, 8 Drawing Sheets
